UNITED STATES PATENT OFFICE

HARRY BUSSINGER, OF PARTRIDGE, KANSAS.

DESIGN FOR A MILLINER'S DISPLAY-TREE.

SPECIFICATION forming part of Design No. 27,313, dated July 6, 1897.

Application filed May 20, 1897. Serial No. 637,456. Term of patent 7 years.

To all whom it may concern:

Be it known that I, HARRY BUSSINGER, a citizen of the United States, residing at Partridge, in the county of Reno and State of Kansas, have invented and produced a certain new and original Design for Milliners' Display-Trees; and I do declare the following to be a full, clear, and exact description of the invention, such as will enable others skilled in the art to which it appertains to make and use the same.

My invention has relation to a new and original design for a milliner's tree which is adapted to support and display hats or goods generally found at a milliner's store; and it consists of a tree of the configuration and ornamentation shown in the accompanying drawing, in which I represent my invention in perspective.

The leading features of my design consist in a vertical standard 1, formed of twisted

wires, and providing three outwardly and downwardly extended legs 2, having lip-shaped feet 3. 4 denotes radiating arms extending laterally from the standard near its upper end and curved upwardly at their outer ends and formed into three distinct branches having loops at their ends. The strands at the extreme upper end of the standard extend laterally in three different directions and are formed with loops. The standard is formed of wires twisted in the shape as shown and presents a very neat appearance.

What I claim is—

A design for a milliner's tree as herein shown and described.

In testimony whereof I hereunto affix my signature in presence of two witnesses.

HARRY BUSSINGER.
